UNITED STATES PATENT OFFICE.

JOHN VIDETTA, OF WEEHAWKEN, NEW JERSEY.

FOLDING LADDER.

Application filed June 13, 1924. Serial No. 719,794.

To all whom it may concern:

Be it known that I, JOHN VIDETTA, a subject of the King of Italy, residing at Weehawken, in the county of Hudson and State 5 of New Jersey, have invented certain new and useful Improvements in Folding Ladders, of which the following is a specification.

This invention relates to certain new and 10 useful improvements in folding ladders wherein the cross rungs of the ladder are pivotally connected at their ends to the side rails to permit the side rails to be moved toward each other for collapsing or folding 15 the ladder and to facilitate transportation of the same and protection to the rungs when being handled.

A further object of the invention is to 20 provide a folding ladder wherein the side rails are formed of hinged sections capable of being folded to present a ladder of the step-ladder type with brace bars extending between the sections of the side rails for holding the same in set up position as a 25 step-ladder.

With the above and other objects in view 30 as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

35 Figure 1 is a front elevational view of a folding ladder constructed in accordance with the present invention, and in extended position,

40 Figure 2 is an edge elevational view of the ladder,

Figure 3 is a front elevational view showing the hinged sections of the side rails of the ladder moved to a step-ladder formation,

45 Figure 4 shows the ladder in folded position,

Figure 5 is a side elevational view of the ladder, with the brace bars connecting the sections of the side rails,

50 Figure 6 is a fragmentary detail view showing the cross rung adjacent the hinged ends of the ladder sections, and

Figure 7 is a detail sectional view taken on line VII—VII of Fig. 1.

55 The ladder embodies a pair of side rails 1 and 2 with each rail formed of a pair of sections that are hinged together as at 3

intermediate the ends of the side rails. The opposed faces of the side rails 1 and 2 are longitudinally grooved at 4 and cross rungs 5 are pivotally supported at their ends as at 60 6 within the grooved portions of the rails as illustrated in Figs. 1 and 3.

To accommodate folding of the ladder with the side rails 1 and 2 moved into abutting relation, the abutting hinged ends of 65 the sections 1^a of the rail 1 carry outwardly directed enlargements 7 while the opposed faces of the upper and lower ends of the sections 2^a of the rail 2 carry enlargements 8. The outer ends of the enlargements 7 70 are angularly cut as at 7^a and the inner ends of the enlargements 8 are angularly cut as at 8^a, while the enlargements contact each other when the rail sections 1^a and 2^a are folded on their hinge connection 3. The 75 rungs 5 being pivoted at their ends to the side rails, the same are moved into the rail grooves 4 when the rail sections are moved toward each other as shown in Fig. 4 and the angularly cut outer ends of the rail sections 1^a and the abutting ends of the rail sections 2^a respectively engage the angle faces 7^a and 8^a of the enlargements 7 and 8. With the ladder in the folded position 80 shown in Fig. 4, the side rails are retained in abutting relations by the hook 9 engaging the pin 9^a as illustrated. The handle 11 facilitates carrying the device.

In disposing the sectional ladder in step-ladder formation, as shown in Fig. 5, the 85 links 10^a are each pivoted at one end as at 11^a to one of the side rail sections and slotted as at 12 to receive a pin 13 carried by the other side rail section, the links holding the rail sections at the proper angularity for setting up the device in step ladder formation.

When the sections are extended as shown in Fig. 1, an intermediate rung 5^a is located at the hinged connection 3, the rung 5^a being pivoted at its ends to the rail enlargement 7 and the abutting hinged ends of the rail sections 2^a. To hold the ladder sections in extended position, arms 14 hinged to the enlargements 7 have side notches 15 adjacent their outer ends that receive the adjacent rungs 5 and brace the sections and reduce strains on the hinge connections between the ladder sections.

From the above detailed description of the device, it is believed that the construction and operation thereof will at once be 110

understood, and while there is herein shown and described the preferred embodiment of the present invention, it is nevertheless to be understood that minor changes may be made therein without departing from the spirit and scope of the invention as claimed.

• What is claimed as new is:—

- 10 In a ladder of the type described, side rails formed of hinged sections, cross rungs pivoted at their ends to the side rails, the side rails being longitudinally grooved for their entire length to accommodate the rungs when the ladder is folded, lateral extensions on the opposed faces of the rails located at 15 the hinged ends of the sections of one rail and at the outer ends of the sections of the other rail to provide for the complete housing of the rungs when the ladder is folded

and with the side rails engaging, said side rails being adapted to have their sections 20 swung on their hinges to provide a step ladder formation, links connecting the side rail sections to hold the structure in its step ladder formation, an intermediate rung at the hinged ends of the side rails, and oppositely 25 extending brace arms carried by and arranged in parallelism with the extensions located at the hinged ends of one side rail with said brace arms being adapted to hook over the rungs located next above and below the said intermediate rung for holding the sections against folding movement while in extended position or while in the form of a step ladder.

In testimony whereof I affix my signature.
JOHN VIDETTA.
